PHILIP KAPLAN AND JACOB KOHN, OF KOKOMO, INDIANA

ADJUSTABLE HEEL CLAMP FOR SHOEMAKERS

Application filed May 10, 1923. Serial No. 361,966.

Our invention relates to adjustable heel clamps, especially useful in holding high heels during the process of attaching to shoes, and it consists in the constructions, 5 arrangements and combinations of parts herein described and claimed.

It is an object of our invention to provide a clamp which is readily adjusted to accommodate heels of various sizes and shapes.

10 A still further object of the invention is to provide clamping jaws of such formation as to hold the heel in rigid position, while yet preventing the marring or splitting of the heel during the nailing operation of the 15 heel to the shoe.

Additional objects, advantages, and features of invention will be apparent from the following description considered in conjunction with the accompanying drawings forming a part of this application, wherein;

Figure 1 is a perspective view of our clamp;

Figure 2 is a longitudinal section thereof; and

25 Figure 3 is a cross section on the line 3—3 of Figure 2.

In carrying out our invention we provide a support 1 having lateral ears 2, suitably apertured for fastening means. The support 1 may, however, be provided with a central angular recess 3, to accommodate the clamp to the usual repairman's jack.

Upon the support there is integrally formed a head 4, which comprises a clamping jaw 5 and ear 6. The head 4 together with its associated jaw 5 and ear 6 thus presents a figure substantially U-shaped in cross section. The upper surface of the head 4 is planiform and extending longitudinally thereof we provide a rib 7. The rib 7 stops short of the jaw 5 a suitable distance, and closely adjacent the jaw 5 there is an adjusting screw 8. The screw 8 extends vertically and is screw threaded through the head 4 and extends in a plane parallel to the jaw 5. The screw has a supporting head 9 and operating knob 10, whereby the supporting head may be raised or lowered, as desired.

The jaw 5 is enlarged at its upper part 50 and curved to overlie the head 4 slightly.

The enlarged part is suitably rabbeted to receive a resilient pad member 11, this pad preferably being formed of rubber, and of oblong shape, in order to accommodate heels of various sizes, as will be apparent, as the 55 description proceeds.

A longitudinally movable jaw 12 is slidably mounted upon the rib 7. The jaw 12, in the present instance, is substantially V-shaped in top plan, having a smooth lower edge 13, adapted to slide upon the upper surface of the head 4. Upon the rear portion of the jaw 12, there is provided a recess 14 having a rear wall 15. The wall 15 is cut away, as at 16, to permit sliding engagement with the rib 7. It should be noted that the rear portion of the jaw 12 is inclined and presents a jaw of tapered formation extending in the direction of the fixed jaw 5. By this construction, heels of various longitudinal configurations may be readily gripped between the opposed jaws 5 and 12.

The ear 6 is suitably apertured and threaded, intermediate its height, to receive an operating stud 17. The stud 17 comprises a head 18 upon one end, the opposite end being reduced, as at 19 and has a head 20. The head 20 and the reduced portion 19 are split longitudinally as at 21, so that these parts may be compressed for insertion 80 in the aperture 19a of the rear wall 15. As soon as the head 20 has passed through the wall, the head will spring outwardly disposing shoulders beyond the aperture 19a; thus preventing withdrawal of the stud 17. 85

The interior portion of the jaw 12 is preferably provided with a suitable facing 21, which may be sponge rubber, felt or the like, or any other material which will afford the necessary protection to an engaged heel. It should 90 also be noted that the recess 14 permits the facing 21 to flex or swing thereinto, thus accommodating heels of various configurations, yet affording ample support throughout the length thereof.

In the use of our device, a selected heel A is positioned with its ground engaging portion resting upon the support 9 and its flat face B abutting the pad 11. The heel A may be raised or lowered to position the heel a 100

suitable distance above the jaw 5, by manipulation of the screw 8. The operation stud 17 is now rotated to move the jaw 12 into engagement with the rear portion of the heel A.

5 Any degree of pressure may be exerted upon the heel to securely hold it, and due to the pad 11 and the facing 21, all possibility of damaging the heel is obviated. With the heel thus supported the shoe may be readily nailed to

10 the heel.

From the foregoing it will be seen that I have provided a clamp of simple construction, yet efficient in operation, and one, by virtue

15 of its V-shaped clamping jaw, will accommodate heels of various shapes and sizes.

We claim:

1. A work holder comprising a frame having a fixed jaw, provided with a resilient gripping member in its upper portion, a

20 longitudinally movable jaw carried by said frame, said movable jaw comprising a substantially V-shaped gripping member, said V-shaped member having a tapered portion extending from its upper edge inwardly to

25 toward the fixed jaw to accommodate work of various configuration, a flexible lining carried by said movable jaw suspended from its upper portion, the lower parts of said jaws being offset from their upper portions, where-

30 by the work is held by the upper portions of said gripping members.

2. A clamp for the heel of a shoe, comprising a fixed jaw, a movable jaw, and means for moving said movable jaw, said movable

35 jaw being of V-shaped formation with a recess therein and provided with a flexible lining mounted for swinging movement in said recess.

3. A work clamp jaw, comprising a rigid

40 wall, having a projecting portion and a receding portion, and a flexible wall, mounted on said projecting portion for swinging movement in said receding portion.

4. In a work clamp jaw, means for engaging

45 the work, consisting of a rigid wall, having a projecting and a cut-away portion, and a flexible wall mounted on said projecting portion, and swinging in said cut-away portion.

50 5. A work clamp jaw having a rigid wall, a flexible wall supported on said rigid wall for engagement with the work, and means for positively limiting the flexing movement of a portion of said flexible wall.

55 6. A work clamp jaw having a recess, a flexible wall movable into said recess upon engagement with the work, and means for rigidly supporting a portion of said flexible wall.
